CHIROPRACTIC TABLE

Gregers G. B. Kjelgaard, Hoosick Falls, N. Y.

Application July 30, 1936, Serial No. 93,327
Renewed December 14, 1939

6 Claims. (Cl. 128—72)

This invention relates to a novel method of adjusting the vertebrae of the spine by providing a table having means whereby the body of the patient may be turned simultaneously with the adjusting move to the vertebrae.

While a number of adjusting tables have been devised with table top sections that are movable in a variety of positions, the object of this invention is to construct an adjusting table, where the table top is divided into a number of sections having a lateral turning movement in an arc of a circle, the center of which is above the top of the table, the object of these laterally turning sections being to turn the body of the patient at the moment the adjusting move is made to the vertebrae, said table sections having means whereby they may be turned simultaneously with the adjusting move to the vertebrae for the purpose of facilitating moving these in position.

Another object of my invention is to provide means whereby the various table top sections may be locked in a horizontal position so as to permit using the table as an ordinary adjusting table and facilitate getting on and off the table by patient.

Another object of my invention is the construction of the top surface of the main body supporting table sections, which are made concave from side to side to correspond with the convexity across front of body of the patient, so as to better support this on the table.

Another object of my invention is to construct the part of the table supporting the legs of the patient lower than the body supporting part of the table for the purpose of facilitating getting on and off the table by the patient.

A further object of my invention is to provide means on the table whereby the turning of the sections of the table may be operated by the foot or knee of the practitioner.

Still further objects and advantages will appear in the following description in connection with the accompanying drawings in which:

Fig. 1 is a side elevation of the adjusting table.
Fig. 2 is a top plan view of same.

Fig. 3 is a front elevation of the part of the table supporting the head of the patient.

Fig. 4 is a front elevation of the part of the table supporting the main body of the patient taken on the line 4—4 of Figure 1.

Fig. 5 is a front elevation of a main body supporting section and its support on the frame taken on the line 5—5 of Figure 1.

Fig. 6 is a front elevation of the part of the

table supporting the lower body and legs of the patient taken on the line 6—6 of Figure 1.

Fig. 7 is a front view of a modified form of a main body supporting section.

Fig. 8 is a cross-section of the head support of the table taken on the line 8—8 of Fig. 3.

Fig. 9 is a cross section of a main body supporting section and its supporting frame taken on the line 9—9 of Fig. 5.

Fig. 10 is a cross section of part of the mechanism for locking the main body supporting sections in position taken on the line 10—10 of Fig. 5.

Fig. 11 is a side elevation of a modification of table.

Referring now more particularly to the drawings in which similar reference characters indicate similar parts 20 designates the rear legs of rear part of the table, these being fastened to the longitudinal side bars 21, which at their front ends are supported by the legs 22. The side bars 21 are connected together by cross pieces 23, Fig. 6, these having their upper sides formed concave in an arc of a circle.

The rear body support of the table comprises a lower horizontal part composed of the side members 24 united by the cross board 25, and an upward and forward inclined part composed of the side members 26 united by the cross board

27, the cross boards 25 and 27 being covered by suitable cushions 28 and give support to the legs and lower body of a patient. Fastened to under surfaces of side members 24 and cross board 25 are the cross pieces 29, these being placed directly above the cross pieces 23, Fig. 6, and are curved convexly in an arc of a circle at

their under sides to correspond with the concave upper sides of the cross pieces 23 so as to permit rear part of the table to turn in a side direction on its supporting frame. Attached to outer and under sides of the cross pieces 29 in

any suitable manner as by countersunk screws and curved to conform with the curve of the cross pieces 29 are the arcuate track members

30, which extend slightly below the curved under sides of the cross pieces 29 and rest on the track supports 31, which may be flat metal strips attached to the side bars 21 and serving to reduce friction when turning rear table support, this being held in turning engagement with its frame

support by the guide members 32 attached to outer sides of cross pieces 23 and having a projection extending over upper side of track members 30, thus guiding the rear body support and keeping this in place on its frame.

50

55

Connected to the front part of the side bars 21 in any suitable manner as by bolts are the two cross pieces 33, and to upper sides of these are attached in a similar manner the middle longitudinal bar 34 and the two outer longitudinal bars 35, the outer bars at their forward ends being attached to and supported by the legs 36. Hingedly connected to upper and rear part of the bars 35 is the swinging stop member 37, which 5 may be turned inward against bottom of cross board 27 until at right angle with this, it being stopped from swinging past this position by the cross piece 38 and serves in this position to lock the rear support from turning, and when turned 10 forward it permits rear table section to be turned to either side.

The side bars 35 give attachment to a series of upwardly extending supports 39, these being connected together by cross pieces 40, Fig. 5, the 20 upper sides of which are concave and give support to the body supporting sections 41, these being formed in an arc of a circle at their under side and are preferably made concave at their upper side. The middle part of under side of sections 41 25 is grooved 42 and to their outer and lower sides are attached the arcuate track members 43 curved to conform with the downward curve of under side of sections 41 and extending slightly below the under side of these; the arcuate track members 43 resting on track supports 44 attached to 30 upper sides of supports 39 for the purpose of reducing friction in turning of sections 41, these being guided and held in position on the supports 39 by means of guide members 45 attached to 35 the cross pieces 40 and having a projection extending inward over the arcuate track members 43 for the purpose of keeping the sections 41 in position on their supports.

The sections 41 may be locked in horizontal 40 position, so they can not turn, by means of a pair of stop members 46 hingedly connected at their lower ends to blocks 47 Fig. 5 attached to outer sides of supports 39 and with their upper ends engaging the grooves 42 at under sides of 45 sections 41, and for the purpose of assisting in moving the stop members 46 out of and into engagement with the sections 41, the stop members may be provided with knobs 48 and are held in 50 their upward position by means of a pair of flat springs 49 curved inward at their upper end and connected to the blocks 47 at their lower end.

The top sections 41 are provided with suitable 55 cushions 50, and to front side of front section 51 is attached a downward extending board 52, 55 which gives attachment to a U shaped forward extension 53 Fig. 4 provided with a cushion 54 and serving to support the arms and shoulders of the patient when in position on the table.

The various table top sections may be turned 60 individually or may be connected together by any suitable means as by a sliding bolt 55 attached to outer sides of the body supporting table top sections and adapted to engage a corresponding opening 56 in its adjoining section.

For the purpose of more effectively turning 65 the body of the patient, straps 57 may be provided, these straps being fastened at one end to outer sides of the various table top sections, and when placed over the patient's back they may 70 be fastened together by any suitable means as a buckle and serve to hold the patient in more firm contact with the table top sections, so as to make the turning of the patient's back more closely follow the turning of the sections.

The middle longitudinal bar 34 is carried for-

ward beyond the two outer bars 35 and rests on the cross pieces 58 Fig. 3 attached to the upright supports 59. At their upper ends the upright supports have attached the cross pieces 60, these being concave at their upper sides to correspond with the convexity of the cross sections 61, which at their upper sides are united by the cross board 62 with the brace 63 and have on their under sides at the outer edges attached the arcuate track members 64, which slide on friction reducing track supports 65 attached to upper side of supports 59. Guide members 66 are connected to outer sides of cross pieces 60 and have a projection extending over upper surface of arcuate track members 64 for the purpose of guiding and holding the cross sections 61 in position when turning these. The board 62 is provided with suitable cushions 67, which give support for the head of patient, and in order to lock the head support in position when desired, a lock member 68 is provided, this being at its lower end hingedly connected to front side of front cross board and when turned upward engages a curved, flat spring catch 69 attached to the front section 61, it being locked in position by means of the 25 side stops 70, also attached to section 61.

The various body supporting sections may be turned in any manner convenient, as by the hand, knee or foot of the practitioner, however in the drawings I have illustrated the generally 30 preferred form of turning these by foot operated means.

To the lower part of the supporting legs of the table are hingedly connected the foot boards 71, which near their outer ends in any suitable 35 manner as by screw eyes or hooks 72 give attachment to a flexible cord 73 of suitable material as wire, which at its other end 74 is connected in a similar manner to upper part of the table top sections; the cords may be connected 40 at their upper ends to the side of these sections on the opposite side of their foot board attachment. The foot boards may be provided with a plurality of hooks or eyes for attachment of lower ends of cords 73, whereby the degree of turning 45 of the table top sections may be varied to suit the need of various patients. To the top of foot board may be attached any suitable material as rubber for giving the foot of the practitioner a better grip on the foot board and prevent slipping, and also the under side of the foot board 50 may have attached a shock absorber 75 of flexible material as felt or rubber to avoid noise or jar when pressing foot board against floor.

The main body supporting sections may be covered by an extra cushion 76 over the individual 55 cushions of each section.

Fig. 7 illustrates a modified body supporting section adapted to be turned by the knee of practitioner, it being provided with a knee operated 60 suitably cushioned extension 77.

Fig. 11 illustrates the adjusting table with a modified form of mechanism for turning the body supporting sections of the table, which mechanism includes a foot operated board 78 on each 65 side of the table and extending between supporting legs 22 and 36 of table, hingedly connected at their inner edge to said legs. At their upper and outer part the foot boards 78 give attachment to connection means as cables or rods 79, which 70 at their upper ends are attached to the outer ends of the body supporting sections and serve to turn these when the foot board is moved downward, and in order to control the movement of the various body supporting sections independently 75

of each other the cables 19 are made detachable and may be disconnected either at their upper or lower ends by means of eyes or hooks engaging corresponding hooks or eyes on foot boards or table sections, and each table top section being provided with individual turning means, the sliding bolts 55 illustrated in Fig. 1 are dispensed with in this modification of table.

The enclosed drawings illustrate a table with a frame constructed mainly of wood, however any other suitable material as metal may be used, and also the part of the table supporting the main body of the patient may be divided into a greater number of sections than the 3 sections illustrated in Figs. 1, 2 and 11.

While I have illustrated and described the preferred embodiments of my invention, it is desired that such changes and modifications may be made in the construction and arrangement of parts as will properly come within the spirit of the invention and scope of the appended claims.

Having thus described my invention I claim:

1. In a table of the character described, adapted to cause a rotating movement to all the various sections of the spine of a person reclining on the table, a longitudinal supporting frame, a rear table top section mounted upon the frame, a plurality of consecutive body supporting table top sections mounted upon the frame and being substantially wider in their lateral direction of the table than in their anterior-posterior direction of the table, said body supporting table top sections being slidably and rotatively mounted upon the frame, the part of the table top sections engaging the frame having sliding movement in an arc in lateral direction of the table, a head supporting table top section mounted upon the frame at the front end of same, means for locking the slidably turning table top sections to the frame support, and means for releasing these for sliding movement laterally in an arc with the part of the table top sections engaging the frame, the center of the guiding arcs for the table top sections being above the part of the table top on which patient reclines.

2. In a table of the character described, adapted to cause a rotating movement to all the various sections of the spine of a person reclining on the table, a longitudinal supporting frame, a rear, leg supporting table top section mounted upon the frame, a plurality of consecutive main body supporting table top sections mounted upon the frame and being substantially wider in their lateral direction of the table than in their anterior-posterior direction of the table, a head supporting table top section at the front end of table and connected with the frame of table by a frame extension below the shoulder and neck support on front, body supporting, table top section, leaving a deep gap between front body supporting table top section and head supporting table top section, all the various table top sections being slidably and rotatively mounted upon the frame, the part of the table top sections engaging the frame having sliding movement in an arc in lateral direction of the table, the center of the guiding arcs for the table top sections being above the part of the table top on which patient reclines.

3. In a table of the character described, adapted to cause a rotating movement to all the various sections of the spine of a person reclining on the table, a longitudinal supporting frame, a rear table top section mounted upon the frame, a plurality of consecutive body supporting table

top sections mounted upon the frame and being substantially wider in their lateral direction of the table than in their anterior-posterior direction of the table, said body supporting table top sections being slidably and rotatively mounted upon the frame, the part of the table top sections engaging the frame having sliding movement in an arc in lateral direction of the table, a head supporting table top section mounted upon the frame at the front end of same, means adapted to be operated by the foot of the practitioner for rotating the slidably turning table top sections, means for locking the slidably turning table top sections to the frame support, and means for releasing these for sliding movement laterally in an arc with the part of the table top sections engaging the frame, the center of the guiding arcs for the table top sections being above the part of the table top on which patient reclines.

4. In a table of the character described, adapted to cause a rotating movement to all the various sections of the spine of a person reclining on the table, a longitudinal supporting frame, a rear table top section mounted upon the frame, a plurality of consecutive body supporting table top sections mounted upon the frame and being substantially wider in their lateral direction of the table than in their anterior-posterior direction of the table, said body supporting table top sections being slidably and rotatively mounted upon the frame, the part of the table top sections engaging the frame having sliding movement in an arc in lateral direction of the table, a head supporting table top section mounted upon the frame at the front end of same, means adapted to be operated by the knee of the practitioner for rotating the slidably turning table top sections, means for locking the slidably turning table top sections to the frame support, and means for releasing these for sliding movement laterally in an arc with the part of the table top sections engaging the frame, the center of the guiding arcs for the table top sections being above the part of table top where patient reclines.

5. In a table of the character described, adapted to cause a rotating movement to all the various sections of the spine of a person reclining on the table, a longitudinal supporting frame, a rear table top section mounted upon the frame, a plurality of consecutive body supporting table top sections mounted upon the frame, and being substantially wider in their lateral direction of the table than in their anterior-posterior direction of the table, said body supporting table top sections being slidably and rotatively mounted upon the frame, the part of the table top sections engaging the frame having sliding movement in an arc in lateral direction of the table, a head supporting table top section mounted upon the frame at the front end of same, means adapted to be operated by the knee of the practitioner for rotating the slidably turning table top sections, guiding and retaining means for keeping the various table top sections in turning engagement with the frame, means for regulating the degree of rotation of the various turning table top sections, means for locking together two or more adjoining sections for turning these simultaneously, means for locking the slidably turning table top sections to the frame support, and means for releasing these for sliding movement laterally in an arc with the part of the table top sections engaging the frame, the center of the guiding arcs for the table top sections be-

ing above the part of the table top on which patient reclines.

6. In a table of the character described, adapted to cause a rotating movement to all the various sections of the spine of a person reclining on the table, a longitudinal supporting frame, a rear supporting table top section mounted upon the frame, a plurality of consecutive main body supporting table top sections mounted upon the frame and being substantially wider in their lateral direction of the table than in their anterior-posterior direction of the table, a shoulder and neck support comprising a forward extension connected to front side

of the body supporting section at the front part of table and being substantially of less width than the body supporting section to which it is attached, a head supporting table top section mounted upon the frame at the front end of same, all the various table top sections being slidably and rotatively mounted upon the frame, the part of the table top sections engaging the frame having sliding movement in an arc in lateral direction of the table, the center of the guiding arcs for the table top sections being above the part of the table top on which patient reclines. 5 10

GREGERS G. B. KJELGAARD.
